UNITED STATES PATENT OFFICE.

FRANK L. HARMON, OF BEVERLY, MASSACHUSETTS, ASSIGNOR TO UNITED SHOE MACHINERY CORPORATION, OF PATERSON, NEW JERSEY, A CORPORATION OF NEW JERSEY.

STAPLE-MAKING MACHINE.

Application filed February 20, 1919. Serial No. 278,154.

To all whom it may concern:

Be it known that I, FRANK L. HARMON, a citizen of the United States, residing at Beverly, in the county of Essex and State 5 of Massachusetts, have invented certain Improvements in Staple-Making Machines, of which the following description, in connection with the accompanying drawings, is a specification, like reference characters on 10 the drawings indicating like parts in the several figures.

This invention relates to apparatus for making staples and has for its general object the provision of improved mechanism 15 of simple construction which will produce staples rapidly and economically and will be reliable and generally satisfactory in operation.

Another object of the invention is to de- 20 vice mechanism for producing staples of the general type which the machine disclosed in Patent No. 1,282,225, granted on my co-pending application Serial No. 12,142, filed March 4, 1915, is adapted to insert for at- 25 taching buttons to shoes, such a staple being disclosed in my Patent No. 1,262,782, granted April 16, 1918. To this end, an important feature of the invention resides in the provision of improved means for au- 30 tomatically forming a blank into a staple having a recess in the bar of the staple con- 35 structed to receive the eye of a shank button. In accordance with the invention, the mechanism forms the recess in the bar of the staple with a substantially straight elongated longitudinal wall upon which the button may adjust itself and the ends of the bar of the staple with stock engaging portions joining the recessed portion of the bar 40 with the legs and adapted to lie flat on the stock. The invention, however, in various aspects is not restricted to use in making staples of this particular form, and important features of the invention reside in the 45 general organization provided for moving the blank transversely into the field of operation of devices which bend the ends of the blank substantially at right angles to the intermediate portion of the blank to form 50 the blank into a staple and for swaging points on the ends of the blank.

Preferably and as illustrated, the blanks are moved into the field of operation of the bending and swaging devices by mechanism

which presses the blank against a movable 55 member and carries it forward with said member and said devices are arranged with their ends interposed in the path of movement of the ends of the blank and operate to bend the ends of the blank to form the 60 blank into a staple and to swage anchor-shaped points on the ends of the blank. As shown, also, the movable member is constructed to serve as a die for shaping the central portion of the blank which constitutes the bar of the completed staple, and the extent to which the bar of the staple is swaged by the die and the mechanism for 65 pressing the blank against the face of the die is capable of being regulated by adjustment of the range of movement of the die. The die and the pressing mechanism are preferably formed with aligned grooves 70 which prevent displacement of the blank relatively thereto and also determine, under 75 certain conditions of operation of the die, the cross-sectional contour of certain portions of the bar of the staple. The movement of the die away from the field of operation of the staple forming devices is limited 80 in such manner that the pressing means is withdrawn from the face of the die thus permitting the discharge of the completed staple.

Other objects and features of the invention 85 relate to various combinations and arrangements of parts and will appear as the description proceeds and be pointed out in the appended claims.

In the drawings:

Figure 1 is a view in perspective of my improved staple making machine;

Fig. 2 is an enlarged view in detail showing the wire guide, the cutter, and the staple forming instrumentalities in the relative positions which they occupy at the point in the cycle of operations of the machine at which the feeding of the wire is completed;

Fig. 3 is a detailed view of the dies for shaping the bar of the staple showing the wire blank gripped therebetween;

Fig. 4 is a view showing the bar of the staple shaped by the dies, the dies having been moved forwardly and the ends of the wire having been bent along the sides of one of the dies by the swaging devices;

Fig. 5 is a view showing the swaging devices moved forwardly to press the ends of

the blank closely against the sides of one of the dies and to swage points on the ends of the blank; and

Fig. 6 is a view of a staple produced by my improved staple making machine.

In the illustrated embodiment of my invention, the frame 2 of the machine is provided with bearings 4 and 6 in which is journaled a drive shaft 8, upon which are mounted the driving pulley 10 and the cams 12, 14, 16 and 18.

In a part 20 of the frame 2, hereinafter sometimes termed the "wire guide" is formed a passage 22 through which passes the stock in the form of a wire A from which the staples are formed. Retrograde movement of the wire A in the passage 22 is prevented by a clutch 24 which comprises a ball or the like received within a tapered recess 26 formed in the wire guide 20 at one side of the passage 22 and so arranged that retrograde movement of the wire A in the passage 22 tends to move the ball toward the restricted portion of the recess thereby wedging the wire against the opposite wall of the passage 22. A spring 28 supplements the action of the wire in moving the ball toward the restricted portion of the recess upon retrograde movement of the wire and yields to permit forward feeding movement of the wire. The clutch 24 is of a form commonly denominated a "Horton clutch" and the construction and manner of operation of such clutch devices is well known, for which reason a more complete description of the clutch is deemed unnecessary.

Means are provided for feeding the wire A through the passage 22 of the wire guide 20, and, as shown, such means comprises a bar 30 extended laterally from the wire guide 20 and having mounted thereon a sliding block 32 formed with a wire passage 34 and provided with a Horton clutch 36 indicated at 38. When the sliding block 32 is moved toward the wire guide 20, the clutch 36 grips the wire A and feeds the wire forwardly through the passage 22 of the wire guide, whereas upon movement of the block 32 rearwardly, the grip of the clutch 36 on the wire A is relieved, and the wire is gripped by the clutch 24 of the wire guide 20 so that it is prevented from partaking of the rearward movement of the block. The block 32 is moved forwardly by the raised part 38 of the cam 18, the motion of the cam being transmitted to the block by a bar 40 slidably mounted in a channeled bracket 42 carried by the frame 2 and provided at 44 with rack teeth geared to a sector gear 46 which, in turn, is geared to the block 32 through the instrumentality of a toothed bar 48 depending from the block 32. Rearward movement of the block 32 to grip the wire A preparatory to a suc-

ceeding feeding movement of the wire is effected by a spring 50 seated in a recess formed in the channeled bracket 42. The spring 50 operates on a foot 52 depending from the slide 40 and co-acting with an adjustable screw 54. The movement of the block 32 rearwardly can be varied by adjusting the screw 54 thereby to regulate the extent of the feeding movement imparted to the wire A.

The wire guide 20 is formed with a recess in which is secured the hardened shear plate 56. Means are provided for co-operating with the shear plate 56 to sever from the wire A the lengths or blanks of wire which are to be formed into staples. As shown, said means comprises a cutter 58 recessed into a slide 60 which is mounted on the wire guide 20. A cam roll 62 on the slide 60 rides on the surface of the cam 16, the slide being operated positively by the cam 16 in a direction to effect severance of the blank from the wire A by the cutter 58. The slide 60 and cutter 58 are retracted after the severance of the blank from the wire by a spring 64 acting against a shoulder formed on the slide 60 and a shoulder 66 on the wire guide 20. The mechanism thus far described constitutes in itself no part of the present invention and may be made of any suitable character without departing from the invention as defined in the claims.

The means whereby the blank cut off from the wire A by the cutter 58 is formed into a staple will next be described. Preferably, and as shown, said means comprises a movable member 68 against which the blank is pressed by a plunger 70 and swaging devices 82 and 84 for bending the blank. The operating means for the plunger comprises a slide 72 into which the plunger 70 is recessed, said plunger 72 carrying a roll 74 acted upon by the cam 14 to move the plunger 70 positively toward the member 68. The plunger 72 is maintained against the surface of the cam 14 by any suitable means. Consequently, the cam 14 gives to the plunger 70 a constant range of movement predetermined by the degree of eccentricity of the cam. The member 68 is normally urged toward the plunger 70 by a spring 76 recessed into the member 68 and operating against a lug 78 projecting upwardly from the frame 2. The movement of the member 68 under the impulse of the spring 76 is limited by the engagement of the end wall of the recess with the lug 78 and the movement of such member in the opposite direction is adjustably limited by a stop in the form of a set screw 80. The lug 78 maintains the member 68 in a position such that when the wire A is fed forwardly by the block 32, the portion of the wire which constitutes the blank which is to be formed into a staple is projected across

and in close proximity to the face of the member 68. The plunger 70 is thrust forward by the cam 14 concurrently with the severance of the blank from the wire A in such manner as to grip or press the severed blank against the face of the member 68. The cam 14 continues the forward movement of the plunger subsequently to the gripping of the blank between the plunger and the member 68, and the blank and the member 68 are thereby carried forwardly in opposition to the spring 76.

The swaging devices 82 and 84 are interposed in the path of movement of the ends of the blank when moved by the plunger 70 and are operable to bend the ends of the blank substantially at right angles to the adjacent portions of the blank to form the blank into a staple. As shown, such devices are so formed and so operated as to swage anchor-shaped points on the ends of the blank. To this end, the swaging devices 82 and 84 are provided with beveled portions 85 extending outwardly beyond their substantially plane faces 86. The shear plate 56 and cutter 58 are so formed as to sever the blank with substantially square ends, and upon engagement of the beveled portions 85 of the swaging devices 82 and 84 with the ends of the blank, the material at the ends of the blank is forced outwardly, whereby substantially anchor-shaped points are formed on the ends of the blank, as indicated in Fig. 6. Points of the character with which the staples produced by my improved machine are provided possess conspicuous advantages, among which may be cited the fact that they resist to a superior degree the separation of the staple and the stock into which it is inserted.

As shown, the movable member 68 serves as a die to impart to the bar of the staple the desired longitudinal contour. It is deemed preferable to form the blank into a staple having a recess in the bar of the staple constructed to receive the eye of a shank button and to permit the shank button to be adjusted on the wall of the recess in the direction of the bar of the staple, wherefore the die 68 is formed with a recess 88 having its base 89 formed as a substantially straight portion elongated relatively to the width of the lips 90 formed on the die at each side of the recess 88. The recess of the bar of the staple is formed in the recess 88 of the die and of corresponding form. In order that the ends of the bar of the staple at the sides of the recess may be caused to lie flat against the surface of the stock adjacent to the recess as well as at other points so as to prevent the eyes of the button from wedging under the ends of the bar the surfaces of the lips 90 which shape the ends of the bar are arranged substantially at right angles to the sides of the re-

cess 88. The plunger 70 also operates as a die and is provided with a projection 92 which is constructed and arranged to fit into the recess 88 of the die 68. The lips 90 of the die 68 and the projection 92 of the die 70 are preferably, and as shown, provided with aligned grooves 94 and 96 respectively, which in the position in which they initially grasp the wire are aligned substantially with the passage 22 of the wire guide 20. The grooves 94 and 96 preclude displacement of the blank relatively to the dies 68 and 70 after it has been engaged thereby.

The stop 80 preferably operates to discontinue the forward movement of the die 68 at a point such that the face of the die is spaced from the face of the die 70 when the latter is at the forward limit of its movement by a distance less than the thickness of the blank. The blank is consequently compressed or swaged between the face of the die 70 and the base 89 of the recess 88 and the faces of the lips 90 of the die 68 to an extent determined by the position of the stop 80, it being apparent that the sooner the die 68 engages the stop 80, the greater is the compression of the blank by the dies. The blank is thus flattened and the cross-sectional contour of the blank changed except where it is engaged in the grooves 94 and 96 which are preferably made of a transverse size equal to or a little greater than half the area of a cross-section of the blank. In the operation of the illustrated construction, therefore, the inner surface of the blank at the shoulders 100 and the outer surface of the wall 98 of the recess in the bar of the blank are flattened, whereas the outer surface of the blank at the shoulders 100 and the inner surface of the wall 98 of the recess of the blank are made rounded or convex. It is particularly advantageous to form the shoulders 100 of the blank with flattened inner surfaces since such portions of the staple constituted by the blank are thereby permitted to fit closely upon the stock, and the staple is thus enabled to take a firmer grip on the stock. It will be apparent that the stop 80 may if desired be adjusted so as to permit the die 68 to participate of the full forward movement of the die 70 and that in such a case, the blank will be shaped or swaged only as to its longitudinal contour and will not be compressed to an extent to swage it transversely or to change its cross-sectional contour.

The swaging devices 82 and 84 are carried by arms 102 and 104 pivoted respectively at 106 and 108 on the frame 2. The arm 102 is provided with a cam roll 108 which is engaged by the cam 12 in a manner such as to move the swaging device 82 in a direction to swage a point on the end of the blank. The arm 102 is moved in the opposite direction by suitable means

(not shown). The arm 104 is provided with a cam roll 110 which is operated by the cam 18 to move swaging device 84 into engagement with the other end of the blank. 5 Reverse movement of the arm 104 is effected by a spring 112 operating against the frame 2 of the machine. The swaging devices 82 and 84 are seated in recesses formed in the arms 102 and 104 respectively and 10 are arranged to be adjusted in said recesses by screws 114 and to be maintained in the positions of adjustment to which they may be moved by locking screws 116. Adjustment of the swaging devices 82 and 84 relatively to the arms 102 and 104 respectively permits the movements of the swaging devices to be so regulated that they may be brought into such relation with the sides of the die 70 as properly to swage the ends 20 of the wire.

A shelf 118 is provided on the frame 2 at the sides of the dies 68 and 70 opposite the wire guide 20. The shelf is rounded as indicated at 120, Fig. 2, so that if the 25 projecting length of wire should tend to sag at the end, it will be cammed upwardly by the surface 120 of the shelf 118 into proper relation with the dies 68 and 70 so as to enter the grooves 94 and 96 of said 30 dies when the dies are brought together upon the wire.

The cam 14 which operates the die 70 is so formed as to permit the die 70 to be moved rearwardly away from the field 35 of operation of the swaging devices 82 and 84 to an extent such as to withdraw the die 70 from the die 68 subsequently to the engagement of the die 68 with the lug 78. The withdrawal of the die 70 from the die 40 68 releases the grip of the dies on the blank which at this stage of the cycle of operations of the machine is formed into the completed staple. Despite the release of the staple by the dies 68 and 70, it may not 45 be properly discharged from the machine but may adhere to the plunger or die 70 and be withdrawn with said die from the die 68. To the end that the proper discharge of the staple may be assured, means 50 are provided for engaging the staple subsequently to its release by the dies 68 and 70 and for detaching it from the die 70. Preferably and as shown, such means comprises a plate 122 which may conveniently 55 be formed of sheet metal. The plate 122 is secured to the frame 2 of the machine at 124 (Fig. 1) and is formed with a bifurcated end 126 which embraces the end of the plunger 70.

60 A plate 128 secured to the frame 2 overlies and confines the slides 60 and 72.

The operation of the machine will, it is believed, be fully comprehended from the foregoing description, but may be briefly 65 summarized as follows. Upon the rotation

of the main shaft 8 the raised portion 38 of the cam 18 is brought into operative engagement with the slide 40 thereby moving the sliding blocks 32 in a direction to feed the wire A through the passage 22 of 70 the wire guide 20. When the feeding movement of the wire A has been completed and simultaneously with the retraction of the slide 32 preparatory to the feeding of another length of wire, the cutter 58 is thrust 75

forwardly by the cam 16, and severs the projecting length of wire against the shear plate 56. The die or plunger 70 is moved forward by its cam 14 synchronously with the forward movement of the cutter 58, and the projection 92 of the die 70 engages the length of blank of wire between the lips 90 on the die 68 prior to the completion of the severance of the wire by the cutter 58, whereby displacement of the blank subsequent 85

to its severance from the wire A is prevented. Such position of the parts is indicated in Fig. 1. At such point in the cycle of operations of the machine, the 90 swaging devices 82 and 84 are in their retracted positions and are retained in such positions as the die 70 is advanced relatively to said swaging devices. When the cutter 58 has been thrust forward far enough to complete the severance from the 95 wire A of the blank which is to be formed upon the wire.

The cam 14 which operates the die 70 is so formed as to permit the die 70 to be moved rearwardly away from the field 100 of operation of the swaging devices 82 and 84 to an extent such as to withdraw the die 70 from the die 68 subsequently to the engagement of the die 68 with the lug 78. The withdrawal of the die 70 from the die 68 releases the grip of the dies on the blank which at this stage of the cycle of operations of the machine is formed into the completed staple. Despite the release of the staple by the dies 68 and 70, it may not 105 be properly discharged from the machine but may adhere to the plunger or die 70 and be withdrawn with said die from the die 68. To the end that the proper discharge of the staple may be assured, means 110 are provided for engaging the staple subsequently to its release by the dies 68 and 70 and for detaching it from the die 70. Preferably and as shown, such means comprises a plate 122 which may conveniently be formed of sheet metal. The plate 122 is secured to the frame 2 of the machine at 124 (Fig. 1) and is formed with a bifurcated end 126 which embraces the end of the plunger 70. 115

120 A plate 128 secured to the frame 2 overlies and confines the slides 60 and 72. The operation of the machine will, it is believed, be fully comprehended from the foregoing description, but may be briefly 125 summarized as follows. Upon the rotation 130 of the blank, which is gripped by the dies and which constitutes the bar of the completed staple, in the recess of the die 68. The swaging devices 82 and 84 then complete their inward movement and swage the ends of the blank, thereby forming points on the

ends of the blank. The swaging devices 82 and 84 are next retracted following which the roll 74 is permitted by a relatively low portion of the cam 14 to move 5 rearwardly, thus permitting movement of the dies 68 and 70 away from the field of operation of the swaging devices 82 and 84. During the first part of the backward movement of the die 70, the die 68 is caused 10 to follow the die 70 by the spring 76 and consequently the staple remains gripped between the dies. Movement of the die 68 is, however, limited by the lug 78 and, after engagement of the die 68 with the 15 lug 78, the die 70 is moved away from the die 68, thereby releasing the grip of the dies on the wire. If the staple adheres to the die 70 subsequent to the release of the staple by the dies, it is brought by the 20 movement of the die 70 into engagement with the detaching or knock-off device 122. The feeding block 32 is then again operated to feed the wire forwardly and the operation of the machine is continued as hereinabove set forth.

Having fully described my invention, what I claim as new and desire to secure by Letters Patent of the United States is:

1. In a machine of the class described, 30 means for gripping a blank comprising a plurality of elements, means for moving the gripping means, swaging devices interposed in the path of movement of the ends of the blank when moved by the gripping 35 means and functioning to bend the ends of the blank against the sides of one of the elements of the gripping means, and means for operating the swaging devices to form points on the ends of the blank.
2. In a machine of the class described, 40 means for gripping a blank between its ends, means for moving the gripping means, swaging devices interposed in the path of movement of the ends of the blank when 45 moved by the gripping means, each of said swaging devices comprising a beveled portion, and means for operating the swaging devices to move the beveled portions thereof into engagement with the ends of the blank thereby to form points on the ends of the blank.
3. In a machine of the class described, 55 means for forming a blank into a staple comprising complementary dies for shaping the central portion of the blank which constitutes the bar of the staple, means for moving said dies, swaging devices interposed in the path of movement of the ends of the blank when moved by said dies and 60 serving to bend the ends of the blank substantially at right angles to the central portion of the blank and along the sides of one of said dies, and means for operating the swaging devices to form points on the 65 blank.

4. In a machine of the class described, means for forming a blank into a staple having a recess in the bar of the staple constructed to receive the eye of a shank button, said means comprising a die formed with a recess of a shape similar to the recess to be formed in the bar of the staple, means for pressing the blank into the recess of the die, means for moving the pressing means and the die thereby to move the 75 blank, swaging devices interposed in the path of movement of the ends of the blank and operable to bend the ends of the blank substantially at right angles to the adjacent portions of the blank, and means for operating the swaging devices to form points 80 on the ends of the blank.

5. In a machine of the class described, a frame, means carried by said frame for forming a blank into a staple having a recess in the bar of the staple constructed to receive the eye of a shank button, said means comprising a die formed with a recess of a shape similar to the recess to be formed in the bar of the staple, means for pressing 90 the blank into the recess of the die, means for moving the pressing means and the die thereby to move the blank, swaging devices pivotally mounted on the frame forwardly of the face of the die, said devices being 95 interposed in the path of movement of the ends of the blank and being operable to bend the ends of the blank substantially at right angles to the adjacent portions of the blank, and means for operating the swaging 100 devices to form points on the ends of the blank.

6. In a machine of the class described, means for forming a blank into a staple comprising complementary dies for shaping 105 the central portion of the blank which constitutes the bar of the staple, means for moving said dies, and means for bending the ends of the blank substantially at right angles to the adjacent portions of the blank 110 and for forming points on the ends of the staple, said bending and point-forming means being interposed in the path of movement of the blank when moved by the dies and said dies being provided with transverse aligned grooves to prevent displacement of the blank relatively to the dies.

7. In a machine of the class described, means for forming a blank of round wire into a staple having a recess in the bar of the staple constructed to receive the eye of a shank button, said means comprising means for bending the ends of the blank substantially at right angles to the central portion of the blank thereby to form a 125 staple, and complementary dies constructed to form the portions of the bar of the staple at each side of the recess with substantially plane inner surfaces and to form the wall of the recess extending in the direction of 130

the end portions of the bar with a substantially plane outer surface.

8. In a machine of the class described, means for gripping a blank, means for moving the gripping means, swaging devices interposed in the path of movement of the blank when moved by the gripping means, and means for operating the swaging devices to form substantially anchor-shaped points on the blank.

9. In a machine of the class described, a die provided with a recess having a substantially straight, elongated wall extending in a plane parallel with the spaced operating end faces of the die and connected therewith by plane surfaces arranged at right angles to the wall, and means movable toward the die for forcing the blank material into the die recess and against the said end faces and for bending the ends of the blank angularly of the intermediate portions of the blank at points spaced from the recessed portion of the blank to form a staple having a bar provided with a rectangular recess to receive the eye of a shank button so that the latter may adjust itself on the recessed portion of the bar, said staple being further provided through the operation of the said end faces of the die with stock engaging portions connecting the recess and the legs of the staple and adapted to lie flat on the work.

10: In a machine of the class described, means for forming a blank into a staple having a rectangular recess in the bar of the staple constructed to receive the eye of a shank button, said means comprising complementary dies, one of said dies being formed with a rectangular recess and the other of said dies having a projection formed thereon constructed and arranged to fit into said recess, said first-mentioned die being provided with grooves in its operative end face at each side of said recess and extending in a direction transverse of the recess, said last-mentioned die having its projecting portion formed with a groove arranged to align with the grooves of the first-mentioned die, and means for bending the ends of the blank substantially at right angles to the recessed portion of the blank to complete the formation of the staple, the recessed portion of which is produced by the co-operation of the first mentioned dies, the construction and arrangement being such that the unrecessed portion of the cross bar of the staple is swaged by the co-operative ends of the dies to produce flat surfaces for lying in close contact with the stock into which the staple may be driven.

In testimony whereof I have signed my name to this specification.

FRANK L. HARMON
